UNITED STATES PATENT OFFICE.

JOHN T. GALBREATH, OF CYNTHIANA, KENTUCKY.

SPARK-PLUG-CLEANING DEVICE.

1,347,366.

Specification of Letters Patent.

Patented July 20, 1920.

Application filed August 4, 1919. Serial No. 315,235.

To all whom it may concern:

Be it known that I, JOHN T. GALBREATH, a citizen of the United States, residing at Cynthiana, in the county of Harrison and

5 State of Kentucky, have invented certain new and useful Improvements in Spark-Plug-Cleaning Devices, of which the following is a specification.

The invention relates to a spark plug 10 cleaning device, and has for its primary object to provide a device of this character wherein the threaded end of a spark plug can be engaged in the body of the device, which is adapted to contain gasoline or 15 other cleaning medium so that the points of the electrodes can be readily cleaned of carbon or other sediments formed thereon, the points being acted upon by a brush confined within the body of the device which is manually controlled for the thorough cleaning of 20 said points.

Another object of the invention is the provision of a device of this character, wherein the construction thereof is novel 25 in form so that the body of the same will receive the cleaning fluid, which can be readily held therein without the possibility of the spilling of the fluid therefrom when in the act of cleaning the electrodes at the 30 points thereof of a spark plug, the body when not attached to the spark plug being closed through the medium of a removable cap so that the contents of the cleaning medium can be retained therein.

35 A further object of the invention is the provision of a device of this character, which is extremely simple in construction, handy for use, readily and easily attached to and removed from a spark plug, thoroughly 40 reliable and efficient in its purpose, and inexpensive to manufacture.

With these and other objects in view, the invention consists in the features of construction, combination and arrangement of 45 parts, as will be hereinafter fully described, illustrated in the accompanying drawings, and pointed out in the claims hereunto appended.

In the accompanying drawings:

50 Figure 1 is a vertical longitudinal sectional view through the spark plug cleaning device constructed in accordance with the invention, showing the spark plug attached thereto.

55 Fig. 2 is a view similar to Fig. 1 show-

ing the brush removed and the open end of the body of said device fitted with a removable plug or cap.

Fig. 3 is a transverse sectional view through the stem of the brush of the device 60 looking toward the stock for the bristles of the brush.

Similar reference characters indicate corresponding parts throughout the several views in the drawing.

Referring to the drawing in detail, the spark plug cleaning device comprises a cylindrical body 5, preferably made from metal open at one end and closed at the opposite end, the open end of said body being 70 formed with a thickened rim 6 having suitable internal threads for detachable connection thereof with the threaded portion 7 of a spark plug 8 of the ordinary well known construction having the usual electrodes 9 75 and 10 respectively which project into the body 5 when the said spark plug 8 is connected therewith, as is clearly shown in Fig. 1 of the drawing.

The internally threaded open end of the 80 body 5 at the thickened rim 6 thereof when detached from the spark plug 8 is adapted to receive a screw plug 11, having a knurled head 12, and this plug serves as a stopper or closure cap for the open end of the body 85 5 of the device.

The closed end of the body 5 has formed therewith a central tubular guide column 13 which extends from the closed end of the body 5 interiorly of the latter for a considerable distance of the length thereof, the inner end of the column 13 being formed with a suitable packing seat for accommodating a packing 14, while the opposite outer end of said column opens through the closed 95 end of the body 5, and in this column is adapted to be received the stem 15 of a brush stock 16, the latter being of disk form to snugly fit within the body 5 and carries a group of tufted bristles 17 constituting the 100 brush proper for action upon the points of the electrodes 9 and 10 of the spark plug 8 when fitted in the device.

The stem 15 projects outwardly beyond the closed end of the body 5 and has suitably secured thereto a knurled knob or finger engaging head 18 so that the stem 15 can be readily rotated in the column 13 for the turning of the brush 17 within the body 5 for action upon the points of the 110

electrodes 9 and 10 of the spark plug to clean said electrodes for the removal of carbon and other sediment therefrom.

The packing 14 seated within the inner 5 end of the column 13 surrounds the stem 15 to avoid any leakage of the contents of the body 5 through the column 13, as will be clearly apparent.

The stock 16 of the brush has formed 10 therein a plurality of holes 19 to permit the passage of the contents of the body 5 therethrough for the wetting of the brush 17 in the use of the device. The body 5 of the device is preferably filled with gasoline, 15 although any cleaning fluid can be introduced into the body 5 to assure removal of carbon or other foreign matter from the electrodes 9 and 10 of the spark plug 8 when connected with the body 5 of the device, as shown in Fig. 1 of the drawing.

By the turning of the knob 18 on the stem 15 of the brush 17, the same can be readily rotated within the body 5 for a sweeping action of said brush over the 25 points of the electrodes of the spark plug and the gasoline or other fluid will cause the easy removal of carbon or other foreign matter as will be obvious. It will be noted that the body 5 can be filled with gasoline 30 and thereafter the plug 11 engaged in the internally threaded open end of said body for closing the same, so that the said device can be carried in the pocket of the user or within a compartment in an automobile 35 for ready and handy use.

From the foregoing, it is thought that the construction and manner of use of the device will be clearly understood and therefore a more extended explanation has been 40 omitted. However, the applicant reserves the right to make changes, variations, and modifications in the invention as fall within the scope of the appended claims without departing from the spirit of the invention 45 or sacrificing any of its advantages.

The length of the stem 15 will permit

longitudinal shifting thereof within the column 13, so as to bring the brush 17 into position for the cleaning of the shell of the spark plug to remove carbon deposits therefrom. Therefore, it will be seen that the electrodes and the end of the body of the spark plug can be thoroughly cleaned in the use of the device.

50

55

What is claimed is:

1. A spark plug cleaning device comprising a hollow body adapted at one end to detachably receive the threaded portion of a spark plug for the positioning of the electrodes of the latter interiorly of said body, 60 and brushing means interiorly of the body for brushing action upon the electrodes of the spark plug to clean the same.

2. A cleaning device for spark plugs comprising a cleaning fluid container having 65 means at one end for detachable engagement on to the threaded portion of a spark plug, a cleaning brush located interiorly of the container for action upon the electrodes of said spark plug, and manually operable 70 means extended exteriorly of the container for actuating the brush.

3. A device of the character described comprising a fluid cleaner container adapted at one end for detachable connection with 75 a spark plug, and a cleaning element interiorly of said container and having apertures for permitting the passage of cleaning fluid from one side to the other thereof.

4. A device of the character described 80 comprising a fluid cleaner container adapted at one end for detachable connection with a spark plug, a cleaning element interiorly of said container and having apertures for permitting the passage of cleaning fluid 85 from one side to the other thereof, and an operating stem for said element projecting exteriorly of the container.

In testimony whereof I affix my signature hereto.

JOHN T. GALBREATH.
